UNITED STATES PATENT OFFICE.

LE GRAND SKINNER, OF ERIE, PENNSYLVANIA.

OIL-PUMP.

SPECIFICATION forming part of Letters Patent No. 632,949, dated September 12, 1899.

Application filed December 13, 1897. Serial No. 661,672. (No model.)

To all whom it may concern:

Be it known that I, LE GRAND SKINNER, a citizen of the United States, residing at the city of Erie, in the county of Erie and State of Pennsylvania, have invented certain new and useful Improvements in Oil-Pumps; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in oil-pumps of the class ordinarily used in mechanism for automatically lubricating engines and other machinery, hereinafter set forth and explained, and illustrated in the accompanying drawings, in which—

20 Figure 1 is a view of the same partially in side elevation and partially in section. Fig. 2 is a transverse section of the same on the line $x-x$ in Fig. 1. Fig. 3 is a longitudinal section of a modified construction of the same.

25 In the drawings, A is the body of the pump, and B the plunger, provided with a stuffing-box C of the usual construction. In the rear 30 end of the body A there is a chamber D, provided with an annular port d , cut into the inside wall thereof and communicating with a suction-inlet E, from which a pipe E', which is provided with a foot-valve e, extends to the 35 oil-supply tank. (Not shown.) The chamber D is also provided with a second annular port d' , which communicates with a discharge-opening F. In this opening there is a check-valve G, which operates as and for the purpose hereinafter described.

40 In the chamber D there is fitted a sleeve H, which extends the entire length of said chamber, the portion H' thereof forming the chamber for a cylindrical valve I, and the portion H² thereof forming a pocket for the valve-spring J, operating on the rear of the valve I. Through the portion H' of the sleeve H radial 45 openings h and h' are cut, which coincide with the annular ports d and d' in the pump-body A. Within the portion H' of the sleeve H the cylindrical valve I is provided with an annular row of radial ports I', which as the

valve moves forward and back in the sleeve H coincide alternately with the suction-ports h and the discharge-ports h' in the sleeve H. 55 From the discharge-opening F there is a small passage f, which leads into the spring-chamber H² and operates to relieve the pressure of any accumulation of oil therein upon the rear of the valve I.

60 It will be observed that the sleeve H, together with the valve I therein, can be readily removed from the pump-body A. When this is done, the check-valve G, which is normally held up off of its seat by the contact of the lower portion thereof with the sleeve H, immediately closes upon its seat and prevents any backward flow of oil from the pipe F', connected with the discharge-opening F of the pump.

70 In Fig. 3 I show a modified construction of my invention. In this figure the positions of the inlet-port d^2 and the discharge-port d^3 are reversed from the positions of the ports in Figs. 1 and 2, and when the plunger B moves back it moves the valve I with it until the end of the valve uncovers the discharge-port d^3 . In all other respects the construction and operation shown in Fig. 3 are the same as that in Figs. 1 and 2 hereinbefore described.

75 In operation as the plunger B is drawn back the valve I is moved forward by the action of the spring J until the ports I' therein coincide with the ports h' in the sleeve H, and as the plunger moves on backward the body 80 of the pump is sucked full of oil; but when the movement of the plunger B is reversed the pressure moves the valve I back, compressing the spring J until the ports I' therein coincide with the discharge-ports h in the sleeve H, when the oil in the pump-body A is forced up and out of the discharge-opening F.

85 Having thus described my invention, what I claim as new, and desire to secure by Letters Patent of the United States, is—

90 1. The combination in an oil-pump, of a pump-body having a suction-port and a discharge-port, a removable internal sleeve or pump-barrel telescoping into said pump-body and having ports therein adapted to register 95 with the ports in the pump-body, a head forming the rear end of said sleeve or pump-barrel and adapted to screw into the rear end of the pump-body, an annular sleeve-valve adapted 100

to reciprocate in said sleeve or pump-barrel having the rear thereof closed, and having radial ports therein adapted to coincide with the ports in the sleeve or pump-barrel, a plunger adapted to enter the open end of said valve, and a spring behind the rear end of said valve, substantially as and for the purpose set forth.

2. The combination in an oil-pump, of a pump-body A having a cylindrical pump-chamber with radial suction and discharge ports therein, a removable cylindrical sleeve or pump-barrel H having radial ports therein and a head closing the rear thereof, adapted to be secured into the rear end of the pump-

chamber, a sleeve-valve I having radial ports therein and closed at its rear end, adapted to reciprocate in said sleeve or pump-barrel, a spiral spring J in a recess H^2 in the head of the sleeve or pump-barrel H adapted to operate against the closed end of the valve I, and a plunger B adapted to enter the open end of said valve, substantially as and for the purpose set forth. 20

In testimony whereof I affix my signature 25 in presence of two witnesses.

LE GRAND SKINNER.
